PAUL TAETZ, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

WIRED RADIO RECEPTION REGULATION

Application filed March 16, 1928, Serial No. 262,314, and in Germany March 29, 1927.

Wire-guided carrier telephony is attended, in practice, with certain technical difficulties which arise when the transmission line is subject to considerable variations in damping. Such difficulties are often caused by the formation of hoar, etc. Hence, it becomes necessary to provide equipment which will insure a practically constant receiving volume in spite of fluctuations in damping or line attenuation.

When connecting radio frequency equipment to ordinary postal wires by means of what is known as the split (duplex) connection, this problem assumes particular importance in so far as the line attenuation between the apparatus should not be unduly low in order that disturbing back-feed by way of the forked connections in both equipments may be precluded. It is occasionally necessary, by establishing looser coupling of the receivers, to artificially raise the attenuation between transmitter and receiver so that even in the presence of optimum line attenuation, operations may be carried on sufficiently far away from regeneration (whistling). An efficient automatic regulation scheme for the amplification factor, looked at from this viewpoint, would give the telephone equipment still further leeway respecting the admissible variations in line attenuation.

To solve the problem, one method would be to simply operate the telephone receiver means, which, comprises essentially demodulator, amplifier means and circuits, under conditions of saturation, so that the signal strength would be limited as soon as a certain state of attenuation of the lines is reached. However, such saturation arrangements are attended with speech distortion and, consequently, their practical application has failed to give satisfaction.

The present invention discloses a system for overcoming the above mentioned defects whereby the telephone receiving apparatus can be regulated, without these inconveniences in an automatic manner in accordance with prevailing line attenuation.

This is insured, according to the invention

by making the prevalent amplification factor of the telephone receiver dependent upon the amplitude of the incoming carrier-frequency potential varying with the line attenuation. To insure the desired dependence of the amplification factor of the receiver upon the amplitude of the incoming carrier-frequency, recourse may be had to similar means as used in radio frequency telephone transmitters for regulating the input amplifiers, and for the prevention of over-modulation by variable voice intensity. (See, for example, German Patent, 445,-575). Also, in the case of the regulating means here disclosed, in order to act upon the amplification factor, variable biasing potentials or "feeble-current resistances" can be employed in known manner. The present invention is distinguished from prior automatic transmitter regulation methods, in so far as the amplification of the receiver is automatically regulated, in dependence upon the potential of the incoming carrier-wave. In this manner, an automatic regulation of the receiver in a satisfactory and distortionless way is insured, a factor particularly important for wire-guided radio frequency telephony.

The desired action, either applied in a steady or intermittent manner, of the regulatory quantities governing amplification (gain regulators or biasing potentials) by the amplitude of the incoming carrier wave can be effected either directly by the aid of electrodynamic, electromagnetic or electro-thermal instruments, one member of which is under the influence of the incoming carrier-wave potential, and whose other mobile part takes care of the adjustment of such amplifier regulation quantities as may be required. However, since instruments of this kind consume comparatively much power, which is usually not available in wire-guided carrier-wave telephony directly at the entrance point of the receiver apparatus, it is a preferable plan in practice to first conveniently increase such regulation energy as has been absorbed for regulation purposes by the aid of suitable amplifiers. The most suitable idea is to use tube circuits for am-

plification whereby the carrier wave is changed into direct current. The ensuing direct current can then be brought to act by suitable direct current instruments upon the 5 regulative quantity to be adjusted, or else the fall of direct current potential across a special resistance can be used for bringing action upon the regulation quantities.

For variable gain regulators and amplification control, instead of solid or liquid ohmic resistances, also tubes can be employed, in known manner, whose effective resistance may be regulated in such a manner, that the grid excitation is influenced in 15 the required manner by the incoming carrier-wave potential.

It will be obvious that regulating means of the above nature will be useful and valuable not only for telephonic apparatus, but 20 that this regulating method will prove of practical use also for telegraphy and tele-mechanical apparatus in which wire-guided radio frequency is employed.

The ideas underlying the present invention 25 are explained in the appended detailed description, reference being made to the accompanying drawing, in which Figs. 1, 2 and 3 schematically disclose three types of circuit embodying the present invention.

30 Fig. 1 shows a circuit arrangement for telephone equipment which is united with existent lines, say, high-potential lines H , by means of radio frequency repeaters or transformers (transformer S_u for the transmitter, and transformer E_u for the receiver) or else through condenser C . The transmitter equipment is indicated by S , the receiver apparatus by E , while the ringing or calling means is denoted by R . The transmitter S 35 and the receiver E are connected with the audio frequency line L_a , L_b through the known forked (split) scheme comprising differential transformer D and line simulation N . The radio frequency equipment above referred to is indicated only in a simple diagrammatic way, because it is generally known and does not form part of the present disclosure. According to the invention, the receiver E is automatically regulated by the 45 incoming carrier-wave potential denoted by V_e .

In the form of construction shown, this regulation is effected through the agency of a gain regulator (potentiometer) R_1 , which 50 in this case is connected in parallel with the output terminals of the receiver E . The incoming carrier-wave potential V_e is transferred either directly, or, as shown, by way of a transformer U to the grid circuit of a rectifier tube G_1 , thereby influencing the plate current of this tube, the latter flowing, if desired, through the stationary coils of an electrodynamic or electromagnetic instrument J .

55 By means of the condenser C_1 and the

choke-coil D' the regulative rectifier effect remains unaffected by transient carrier-wave fluctuations during the call, ring or modulation. The gain regulator R_1 is shown constructed in the form of a liquid rheostat 70 whose stationary electrode c is connected with one of the output terminals, and whose other adjustable electrode b , subject to control by the mobile part a of the instrument J , is united with the other output terminal of 75 the receiver.

It will be understood that the gain regulator R_1 could be designed also in some other way; for example, as a fixed resistance or else as a tube resistance, and instead of being connected with the output terminals, the same could also be associated with any of the grid circuits of the receiver equipment.

In the form of construction shown in Fig. 2, the transmitter, the calling device of the receiver, and the telephony wires have not been shown for the sake of simplicity and the receiver E has been assumed to consist of two tubes 1 and 2. The rectifier tube G_1 , as in the previous embodiment, is influenced by the carrier-wave potential V_e through the transformer U , and the electro-magnetic instrument J , passed by the direct current is here a solenoid which actuates a contact movable along the potentiometer P . In this way, such part of the potential supplied from the battery R_v , as is required for regulation, is applied in the form of a variable biasing potential in the grid circuit of input tube 1 of the receiver apparatus, suitably in parallel 90 relation to a condenser C_2 .

Of course, the receiver can comprise a plurality of stages, and the biasing potential can be controlled in other stages as has hereinbefore been described. Either conjointly with, or else instead of, regulation of biasing potential, a rheostat, or variable resistance, can be controlled or adjusted as before set forth, in the grid circuit of any desired stage. In the case of Fig. 2, this idea is 105 shown by the variable resistance R_1 in the grid circuit of the output tube 2, and the same may consist of a solid, liquid or a tube resistance as above pointed out.

Fig. 3 shows how the fall of potential 110 across a resistance J_1 may be utilized for the purpose of regulating the receiver apparatus. In this arrangement, the plate current of the rectifier G_1 , connected in a manner similar to the previous circuit arrangements, 115 is made to flow through the resistance J_1 , whose terminals are connected in the grid circuit of a receiver tube, say, the input tube 1.

Having thus described my invention what 120 I desire to protect by Letters Patent is as follows:

1. In a wired radio receiving system, a transmitting line over which the incoming carrier is transmitted to the receiver, the at- 130

tenuation of the said transmitting line being variable under different conditions, a receiver including an amplifier upon which the carrier wave is impressed, an electron discharge rectifier connected to said line, 5 means for impressing a portion of said carrier wave upon the input terminals of said rectifier, a capacity connected between the input terminals of said amplifier, a potentiometer connected across said capacity, and 10 means, in the output of said rectifier, to adjust said potentiometer in accordance with the amplitude of the direct current component of the rectified carrier current to compensate for changes in line attenuation. 15

2. In a wired radio receiving system, a transmission line, a source of modulated carrier current for transmitting signals over

the transmission line to the receiver, the attenuation of the transmission line being variable under different conditions, the receiver including an amplifier upon which the modulated carrier wave is impressed, an 70 electron discharge tube rectifier connected to said line and having a portion of said carrier wave impressed upon its input terminals, a capacitive reactance connected between the input terminals of the amplifier, a potentiometer connected across said capacitive reactance, and means including an inductive reactance in the output circuit of said rectifier to adjust said potentiometer in accordance with the amplitude of the direct current 75 component of the rectified carrier current to compensate for changes in line attenuation. 80
